DOOR LOCK

Charles O. Potter, Fullerton, Calif.

Application January 30, 1939, Serial No. 253,649

7 Claims. (Cl. 70—153)

This invention relates to door locks and more particularly to an improved door lock adapted for use with a motor vehicle door.

An object of this invention is to provide a door lock embodying the use of a gear rack and pinion and means for selectively holding the pinion against rotation.

Another object of this invention is to provide a lock of this kind which may be acted upon by three different elements at points remote from the lock mechanism proper.

A further object of this invention is to provide a lock of this kind which is relatively simple in construction so that it will not get out of order.

To the foregoing objects and others which may hereinafter appear, the invention consists of the novel construction, combination, and arrangement of parts as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is a fragmentary side elevation of a door having a lock constructed according to this invention mounted therein.

Figure 2 is a fragmentary horizontal section through the door and door frame.

Figure 3 is a fragmentary sectional view taken on the line 3—3 of Figure 2.

Figure 4 is a fragmentary sectional view taken on the line 4—4 of Figure 3, and

Figure 5 is a fragmentary sectional view taken on the line 5—5 of Figure 2.

Referring to the drawing, the character D designates a hollow or metal door structure which is connected to a door frame F. In the present instance, the door D and the frame F are associated with a vehicle. The frame F on the inner edge thereof is provided with a toothed rack or keeper 10 which is secured to the inner edge of the frame F by means of fastening devices 13. Preferably the rack 10 is disposed in substantially horizontal position and the adjacent wall 11 of the door D is spaced from the adjacent wall 12 of the frame F so as to provide sufficient space between the two walls 11 and 12 to permit the rack 10 to be positioned therebetween.

A rotatable pinion or bolt member 14 is rotatably mounted on a shaft 15 carried by the door D and a portion of the pinion or gear 14 projects through an opening 16 provided in the

wall 11 of the door. When the door D is closed, the pinion 14 is adapted to be positioned as shown in Figure 2, but it will be understood, if desired, that the door D may be maintained in a partly open position with the pinion 14 engaging a selected one of the outermost teeth of the rack 10.

A door handle 17 is positioned on the outer side of the door D and is fixedly mounted on a stem or shaft 18 which is secured to a shaft 19 extending inwardly through the front wall 20 of the door D. A spring 21 is secured at one end to the wall 20 of the door and at the other end to the shaft 19 and normally provides a bias to maintain the handle 17 in a substantially horizontal position. The shaft or stem 18 extends through an escutcheon plate 22 which is secured to the outer wall 20 and the spring 21 is positioned between the plate 22 and the outer wall 20. As shown in Figure 2, the shaft or stem 18 is provided with a recess 23 within which the stub shaft 19 engages and is fixed by means of a pin 24. The stub shaft 19 is provided on the periphery thereof with a spiral key 25 which is adapted to engage in a spiral groove 26 provided in a slide block 27. The block 27 slidably engages the bottom wall 28 of a housing 29 and the block 27 is provided on one side thereof with a laterally projecting lug or arm 30.

A spring pressed pawl 31 is rotatably mounted on a pin or shaft 32 carried by the housing 29 and the bill of the pawl member 31 is adapted to engage the pinion or gear member 14 so as to hold this gear member 14 against rotation in one direction when the pawl 31 is in operative position. A pawl releasing bar 33 is mounted within the housing 29 and is provided with an elongated slot 34 within which a pin 35 carried by the pawl member 31 slidably engages. The bar 33 is provided with an elongated extension 36 which engages through the lug 30 and is secured by means of a pin 37. In this manner, outward movement of the block 27 will pull the pawl member 31 to a released position so that the gear member 14 may freely rotate in either direction.

The pawl member 31 is yieldably held in operative position by means of a spring 38 which is mounted on a pin 39 carried by a bell crank 40. The bell crank 40 is rockably mounted on a pin or shaft 41 extending through the bottom wall 28 of the housing 29, and the bell crank 40 has a pin 42 which slidably engages in a slot 43 carried by one end of an elongated crank operating rod or bar 44. The bell crank 40 is provided with an extension 45 having a pin 46 which

is slidable in the slot 34 and normally engages in the slot 34 at the end opposite from the pin 35.

The bar 44 is slidable in a guide member 47 which is carried by the inner wall 48 of the door 5 D and a spring 49 engages at one end against the lug 47 and at the other end against a collar or flange 50 carried by the bar 44 so as to normally hold the bell crank 40 in a position with the pin 46 at the outer end of the slot 34. A second or inner handle 51 is mounted on a shaft or stem 52 and the shaft 52 extends through the inner wall 48 and a wall 53 carried by a cylindrical housing 54. The housing 54 is provided with an opening 55 through which an extension 56 pivotally carried by the inner end of the bar 44 is adapted to engage. The cylindrical housing 54 is adapted to be fixed relative to the inner wall 48 and a plate or disc 57 is mounted within the housing 54 and is secured to the inner end 20 of the shaft or stem 52. The extension 56 is provided within the housing 54 with a laterally projecting lug or trunnion 58 which is rotatably mounted in an opening 59 within the plate 57 so that rotation of the plate 57 will rock the extension 56 and likewise move the bar 44 longitudinally of the door D. A locking member 60 is slidable through the inner wall 61 of the housing 54 and is constantly urged inwardly by a spring 62. The locking member 60 is adapted to yieldably hold the extension 56 against rotation when the extension 56 is in the position shown in Figure 2 so as to lock the bell crank 40 against rocking movement. Locking of the bell crank 40 against rocking movement in one direction will likewise lock the pawl member 31 against rocking movement to a released position.

A pawl locking bolt 63 is carried by an elongated rod 64 which is slidable through the wall 70 of the housing 29 and slidably engages a lug or extension 65 carried by the pawl operating bar 44. The inner wall 48 of the door D is also provided with a guide member 66 through which the rod 64 slidably engages. A spring 67 is disposed about the rod 64 and at one end engages a collar 68 which is fixed to the rod 64 and normally urges the bolt 63 to a released position. The bar 64 is also provided with a head or collar 69 adjacent the inner end thereof and the lug or extension 65 is slidable between the collar 68 and the collar or head 69. The collar 68 is so positioned on the rod 64 that when the bar 44 moves toward the left, as viewed in Figure 2, the lock bolt 63 will also be moved to the left or to a pawl locking position against the tension of the spring 67. In this locking position, the bar 44 is held against movement to the right by means of the locking member 60 which engages the extension 56.

In order to provide a means whereby the pawl member 31 may be locked from the exterior of the door D, I have provided a key operated locking means which includes a key operating mechanism 71 which is secured to the front wall 20 of the door and includes a keyhole 72 of suitable configuration through which a key is adapted to be projected for operating the mechanism 71. A shaft 73 is connected to the mechanism 71 and is adapted to be rotated upon the rotation of the mechanism 71 by means of a key and a gear or pinion 74 is secured to the inner end of the shaft 73. A second gear or pinion 75 meshes with the gear 74 and is rotatably carried by a bearing 76 securing to the inner wall 48 of the door. An arm 77 or notched member 77 is fixed to the pinion or

gear 75 and is adapted to be swung upwardly upon rotation of the gear 75 in one direction so as to engage a latching device. The latching device comprises a plate member 78 provided with an elongated slot 79 through which a pin 80 engages. The pin 80 is fixed to the inner wall 48 of the door D and a rockable latching plate 81 is mounted on the pin or shaft 80. The rockable latching plate 81 is spring pressed by means of a spring 82 being biased to a lowermost position by 10 means of the spring 82. The sliding plate 78 is provided with a forwardly projecting lug 83 which is loosely positioned in a substantially U-shaped slot 84 provided in the rockable latching plate 81. An upwardly projecting fork 85 is fixed to the 15 sliding plate 78 and projects upwardly through a slot 86 provided in the bottom wall 28 of the housing 29. The fork 85 engages about the rod 64 closely adjacent the inner end of the bolt 63 so that movement of the sliding plate 78 to the 20 left, as viewed in Figure 3, will move the bolt 63 to a locking position.

The sliding plate 78 is provided with a substantially V-shaped cut-out 87 in the lower edge thereof within which one notch 88 of the lug 77 25 is adapted to engage. The lower edge of the latching plate 81 is provided with an arcuate portion 89 with which the notched portion 88 of the lug 77 is adapted to engage. The lug 77 when in released position engages against a stop member 91 and when in locked position engages against a stop member 92 which is secured to the inner wall 48 of the door D on the side of the pinion 75 opposite from the stop member 91.

In the use and operation of this door lock when it is desired to open the door from the outside, the handle 17 is rocked downwardly. This downward rocking of the handle 17 will pull the block 27 outwardly and at the same time rock the pawl member 31 to a released position. The pin 35 40 carried by the pawl member 31 at this time is positioned at the inner end of the slot 34 carried by the plate 33. The door D may then be freely swung to an open position. The door may be swung to a closed position with the handle 17 45 in either a downwardly inclined position with the pawl 31 released from the pinion 14 or, if desired, the handle 17 may be positioned as shown in Figure 1, which is a horizontal position. With the handle 17 in a horizontal position when the door is closed, the pinion 14 will rotate upon engagement with the gear rack 10, and the pawl 31 will yieldably ride over the teeth of the pinion or ratchet 14.

In the event it is desired to lock the door D 55 from the outside, a key is inserted in the keyhole 72 and the shaft 73 then rotated in a clockwise direction. This will rotate the gear 75 in a counter-clockwise direction and swing the lug or arm 77 through an arc which will initially rock 60 the latch plate 81 upwardly until the lug member 83 is at the lower or bight portion of the U-shaped slot 84. In this position, the continued rotation or swinging of the lug 77 will cause the sliding plate 78 to be moved to the left due to 65 the engagement of the notch 88 with the forward edge of the V-shaped opening or recess 87. Forward movement, or movement to the left of the plate 78, will move the fork 85 to the left, as viewed in Figure 3, which will move the locking bolt 63 forwardly or to the left in a position where the bolt 63 will confront the rear of the bill of the pawl member 31. When the plate 78 has been moved forwardly to the limit permitted by 70 the bight of the U-shaped notch 84, the spring 75

82 will swing the latch plate 81 downwardly so that the lug 83 will be in the forward leg of the notch 84. In this position, the sliding plate is locked against sliding movement and the bolt 63 is held in the locked position against the tension of the spring 67.

In the event it is desired to lock the pawl member 31 from inside of the door, the handle 51 may be rocked upwardly so as to move the locking bar 44 to the left as viewed in Figure 3. Movement to the left of the locking bar 44 will bring the lug 65 into engagement with the collar 68 so as to thereby slide the bolt or bar 64 to the left and at the same time slide the locking bolt 63 to a locked position. The bar 44 is held in a locked position when the extension 56 engages beneath the spring pressed holding member 60 carried by the housing 54. At this time, the trunnion or lateral extension 58 carried by the bar 20 extension 56 is substantially in a horizontal position as viewed in Figure 3.

The pawl member 31 may be rocked to a released position inside the door by swinging the handle 51 downwardly so as to draw the bar 44 to the right, as viewed in Figure 3. In the event, the bolt 63 is in a locked position at this time, the lug member 65 will engage the collar 69 so as to forcibly pull the bolt 63 to the right and at the same time the spring 67 will constantly urge the bolt 63 toward a released position. Movement of the bar 44 to the right will rock the bell crank 40 and the extension 45. Rocking of this extension 45 will pull the bar 33 toward the outer wall 20 of the door and thus swing the pawl member 31 to a released position.

I claim:

1. A door lock comprising a rotatable pinion constituting a latching bolt adapted for engagement with a keeper, a spring-pressed pawl pivotally supported intermediate its ends having one of its ends engaging in and normally holding said bolt against rotation in one direction with respect to the keeper, a rotatable pawl releasing member, and means connected to the other end 45 of said pawl, mounted on, engageable with and movable lengthwise relative to said releasing member for shifting said pawl out of normal position on the rotation of the said releasing member in one direction and against the action of the 50 spring pressure applied to the pawl.

2. A door lock comprising a rotatable pinion constituting a latching bolt adapted for engagement with a keeper, a spring-pressed pawl engaging said pinion and normally holding said pinion against rotation in one direction with respect to the keeper, a slidable pawl operator provided including a part formed with a spiral groove and a link connected with the pawl for shifting the latter from normal, and a rotatable shaft provided with a key slidably traveling in said groove for moving said part to a pawl releasing position.

3. A door lock comprising a rotatable toothed locking bolt adapted for engagement with a keeper, a spring-pressed pawl engaging said bolt and normally holding said bolt against rotation in one direction with respect to the keeper, a slotted link connected to said pawl, an endwise movable

member connected to said link, and rotatable operating means operatively connected to said latter member for shifting said pawl to released position.

4. A door lock comprising a rotatable toothed locking bolt adapted for engagement with a keeper, a spring-pressed pawl engaging said bolt and normally holding said bolt against rotation in one direction with respect to the keeper, a slotted link connected to said pawl, an endwise movable member connected to said link, a pawl locking member normally biased to a released position, rotatable operating means operatively connected to said endwise movable member for shifting said pawl to released position upon movement of said endwise movable member in one direction, and means carried by said endwise movable member engaging said pawl locking member for shifting said latter member to a pawl locking position upon movement of said endwise movable member in the opposite direction.

5. A door lock comprising a rotatable toothed locking bolt adapted for engagement with a keeper, a spring-pressed pawl engaging said bolt and normally holding said bolt against rotation in one direction with respect to the keeper, means for releasing the pawl from normal position, a spring-pressed pawl locking member normally disposed in released position, a key actuated slide member, and a fork carried by said slide member engageable with said pawl locking member upon movement of said slide member in one direction for shifting said pawl locking member to a locking position.

6. A door lock comprising a rotatable toothed locking bolt adapted for engagement with a keeper, a spring-pressed pawl engaging said bolt and normally holding said bolt against rotation in one direction relative to the keeper, an elongated slotted bar, means connecting said bar with said pawl for moving said pawl to released position upon movement of said bar in one direction, a rotatable operating member, and a link pivotally connecting said operating member with said bar whereby to move said bar in said one direction to thereby shift said pawl to a released position.

7. A door lock comprising a rotatable toothed locking bolt adapted for engagement with a keeper, a spring-pressed pawl engaging said bolt and normally holding said bolt against rotation in one direction relative to the keeper, an elongated slotted bar, means connecting said bar with said pawl for moving said pawl to released position upon movement of said bar in one direction, a rotatable operating member, a link pivotally connecting said operating member with said bar whereby to move said bar in said one direction to thereby shift said pawl to a released position, a spring-pressed pawl locking member normally urged to a released position, means carried by said bar engageable with said locking member for shifting said locking member to a pawl locking position, and spring-pressed means engageable with said link for yieldably holding said link and bar in pawl locking position.

CHARLES O. POTTER.
